UNITED STATES PATENT OFFICE

154,000

DESIGN FOR A DISPLAY FIGURE

Marguerite T. Upson, Tucson, Ariz.

Application January 5, 1948, Serial No. 143,536

Term of patent 14 years

(Cl. D1—2)

To all whom it may concern:

Be it known that I, Marguerite T. Upson, a citizen of the United States of America, residing at Tucson, in the county of Pima and State of Arizona, have invented a new, original, and ornamental Design for a Display Figure, of which the following is a specification, reference being had to the accompanying drawing, forming part thereof.

Figure 1 is a perspective view taken from the front of a display figure, showing my new design.

Fig. 2 is a perspective view taken from the rear of the display figure.

I claim:

The ornamental design for a display figure, as shown.

MARGUERITE T. UPSON.
